ILLUMINABLE PICTURE FRAME

Walter R. Haycraft, Sylvania, Ohio

Application March 26, 1958, Serial No. 50,184

Term of patent 14 years

(Cl. D29—20)

FIG 1

FIG 3

FIG 2

Figure 1 is a front perspective view of an illuminable picture frame, showing my new design;

Figure 2 is an end elevational view thereof; and

Figure 3 is a top plan view thereof.

The picture shown in broken lines within the illuminable picture frame is for illustrative purposes only.

I claim:

The ornamental design for an illuminable picture frame, as shown and described.
